FLYWHEEL DYNAMO ELECTRIC MACHINE FOR INTERNAL COMBUSTION ENGINES

Filed May 2, 1922

2 Sheets-Sheet 2

UNITED STATES PATENT OFFICE.

RALPH LEONARD ASPDEN, OF CHORLEY, ENGLAND, ASSIGNOR TO THE ASPDEN FLY-WHEEL DYNAMOTOR SYNDICATE LIMITED, OF LONDON, ENGLAND.

FLYWHEEL DYNAMO-ELECTRIC MACHINE FOR INTERNAL-COMBUSTION ENGINES.

Application filed May 2, 1922. Serial No. 557,889.

To all whom it may concern:

Be it known that I, RALPH LEONARD ASPDEN, a subject of the King of Great Britain and Ireland, and residing at 6 Southport Road, Chorley, in the county of Lancaster, England, have invented certain new and useful Improvements in and Relating to Flywheel Dynamo-Electric Machines for Internal-Combustion Engines, 10 of which the following is a specification.

The invention relates to improvements in fly-wheel dynamo-electric machines used for starting the engine particularly of automobile vehicles and especially to those of 15 the kind described in the United States Patent Specification No. 1419607. In the invention therein described, the entire fly-wheel is replaced by the rotary member of a dynamo-electric machine and two clutches 20 are provided, one connecting said rotary member to the crank-shaft and the other serving as the usual main clutch for throwing in the transmission element. In this device, two pedals are provided, one for 25 actuating each of said clutches.

According to the present invention, only part of the usual flywheel is embodied in the rotary member of a dynamo-electric machine, the remainder of the flywheel being mounted as heretofore on the crank-shaft. Such division of the flywheel into 30 two parts permits of the employment of a single instrumentality for operating both clutches without the necessity of introducing 35 any disengagement between said instrumentality and either of the clutches. Thus, for example, when running the main clutch is withdrawn for the purposes of changing gear, or otherwise, that part of the flywheel 40 embodied in the rotary member of the dynamo-electric machine is thrown out of action, but the engine continues to run by virtue of the remaining part of the flywheel mounted on its shaft.

45 The present invention consists in the combinations of parts hereinafter described and particularly pointed out in the claims.

Referring to the accompanying drawings, 50 which are of a diagrammatic nature:— Figure 1 shows a section through one form of dynamotor according to the present invention;

Figure 2 shows as an end elevation the

structure of the brush-carrying ring and its position in relation to the field magnets, 55 while

Figure 3 is a perspective view of one of the auxiliary arcuate clutch members;

Figs. 4 and 5 show sectional views of modified forms of dynamotor according to 60 the present invention,

Fig. 6 is a general view showing the invention in place on a portion of the automobile.

Where desirable, corresponding parts in 65 the different figures are denoted by the same reference symbols.

In carrying the invention into effect according to one form, (see Figure 1) specially applicable to a light motor road 70 vehicle, the stationary member, *a*, of the dynamotor is mounted on a boss, *b*, or the like forming part of the crank case and carries the field magnets, *c*, in a position just outside the boss. The stationary member may be substantially of a disc and sleeve formation, the sleeve, *d*, fitting over 75 the boss and the disc at its outer periphery having mounted on it a ring, *e*, carrying the brush holders, *f*, and brushes, *f'*, the latter alternating in a circumferential direction with the field magnets as shown in Figure 2. The ring, *e*, is split at one point so that by merely loosening a screw, *h*, it can be turned round into any position 85 desired to obtain access to the brush holders and brushes. In addition, one segment or length, *e'*, of the ring between two adjacent brush holders is removable bodily, so that access may be obtained to the commutator, *i*, itself. The latter member and the armature, *k*, are carried by a comparatively thick disc, *m*, from the face of which they project into a position radially between the brushes, *f'*, and the field magnets, *c*. 90 The disc, *m*, is freely mounted on the crank-shaft, *n*, and is adapted by means such as those to be hereinafter described, to be clutched to the flywheel, *o*, itself keyed on the crank-shaft, *n*. The flywheel, *o*, is provided with the outer cone, *r'*, of the usual transmission clutch, the member, *s*, carrying the inner cone, *r*², being withdrawn against 95 a spring, *t*, by the pedal in the usual manner.

It is an advantage of the arrangement described that the commutator *i*, is in a con-

stant position axially in relation to the brushes, f' , while the part which carried the armature in the original form of the invention and interfered somewhat with the silent 5 changing of gear owing to its weight, can be materially lightened.

The special feature of the present invention consists in the arrangement whereby on inserting the main clutch, the armature-carrying 10 or other rotatably mounted member of the dynamotor is automatically clutched to the flywheel or shaft, and for this purpose according to the form illustrated in Figure 1, the clutch is divided into four arcuate 15 portions, (see Figure 3) equally spaced along the circumference of a circle and each provided with a flattened portion u , sliding axially in corresponding slots in the flywheel. To one end of this flattened portion is secured a bevelled member, v , which 20 engages with a corresponding recess in the armature-carrying member, while on a stem, w , projecting from the other end, are mounted in the order given a light spring, x , a washer, z , pinned to the stem, a heavy spring, y , and a second washer, z , slidable on the stem and in contact with the inner member, s , of the main clutch when the latter is 25 in an operative position, movement of the washer in other conditions being limited by a taper pin through the stem or otherwise. The object of providing two springs is to 30 compensate for wear of the main clutch lining.

35 In the form of invention described, to start the engine from rest, the main clutch is withdrawn, the gears being in the neutral position, and current from the battery switched on to the dynamotor. In these 40 circumstances the armature, k , and its carrying member, m , being perfectly free will acquire a high speed and store considerable energy. The main clutch and simultaneously also the 45 auxiliary clutches can then be gradually put in so that the engine is started up.

In accordance with the present invention no disengaging devices are required between the pedal and the clutches, the operative 50 relation of these parts being such that at all times both clutches can be operated from the one pedal.

According to the modification shown in Figure 4, the arrangement of parts is in 55 general similar to that described above but instead of cone clutches, plate clutches are provided in the manner shown. In the main clutch plates, 4 and 5, are associated respectively with the flywheel, o , and member, s , in such a manner that they can slide to a 60 limited extent but cannot turn. Similarly, as regards the auxiliary clutch, plates, 6 and 7, are associated in like manner with the armature-carrying member, m , and the flywheel, o . The one spring, 8, puts pressure 65 on both clutches by way of the pins, 9, slid-

ably mounted on the flywheel, o , so that on depression of the clutch pedal, the armature is automatically freed to rotate on its bearings.

In order to show how the two clutches 70 may be operated from a single instrumentality such as the main clutch pedal, reference is made to Figure 5 where the form of the invention shown in Figure 4 is shown in operative relation to the parts of an automobile with which it is associated. In this figure the main clutch pedal, A , is rigidly mounted on the spindle, B , carrying a lever, C , which is connected by the link, D , to a lever, E , on a parallel spindle, F , another 80 lever, G , rigidly attached to which operates the member, s , of Figure 4 by a pin, H .

Any suitable wiring system may be used in conjunction with the mechanical constructions above described.

The invention may be applied either to stationary internal combustion engines or to internal combustion engines fitted to motor boats, air-craft or other forms of motor vehicle.

Having now described my invention, what I claim as new and desire to secure by Letters Patent is:—

1. In apparatus of the kind indicated, the combination of an engine having a shaft, a dynamo-electric machine having a rotary element co-axial with said shaft, clutch means for placing said rotary element into operative relation to said shaft to form a driving-driven unit, a transmission element, clutch means for connecting said transmission element to said driving-driven unit together with a single instrumentality for operating both said clutch means, said instrumentality being in permanent operative 105 relation thereto, as set forth.

2. In apparatus of the kind indicated, the combination of an engine having a shaft, a dynamo-electric machine having a rotary 110 element co-axial with said shaft, clutch means for placing said rotary element into operative relation to said shaft to form a driving-driven unit, a transmission element, clutch means for connecting said transmission element to said driving-driven unit together with a single instrumentality for simultaneously operating both said clutch means, said instrumentality being in permanent operative relation thereto, as set forth.

3. In apparatus of the kind indicated, the combination of an engine shaft having an attachment in rigid relation thereto, a rotary element of a dynamo-electric machine having a rotary element co-axial with said 125 shaft; means for clutching said rotary element to said attachment, a transmission element, means for clutching said transmission element to said attachment together with a single instrumentality for operating both 130

said clutching means, said instrumentality being in permanent operative relation thereto, as set forth.

4. In apparatus of the kind indicated, the combination of an engine having a shaft, a rotary element of a dynamo-electric machine co-axial with said shaft, and a power-transmission element; means for clutching said shaft, rotary element and power-transmission element together and a single instrumentality for actuating said clutching means, said instrumentality being in permanent operative relation thereto, as set forth.
5. In apparatus of the kind indicated, the combination of an engine having a shaft, a rotary element of a dynamo-electric machine co-axial with said shaft, and a power-transmission element; means for simultaneously clutching said shaft, rotary element and power-transmission element together

and a single instrumentality for actuating said clutching means, said instrumentality being in permanent operative relation thereto, as set forth.

6. In apparatus of the kind indicated, the combination of an engine having a shaft; a flywheel mounted on said shaft; a rotary element of a dynamo-electric machine co-axial with said shaft, said rotary element also serving as a flywheel; and a power-transmission element; means for clutching said shaft, rotary element and transmission element together and a single instrumentality for actuating said clutching means, said instrumentality being in permanent operative relation thereto, as set forth.

In testimony whereof I have signed my name to this specification.

RALPH LEONARD ASPDEN.
